Application August 31, 1934, Serial No. 742,276
In Denmark October 2, 1933

9 Claims. (Cl. 70—9)

This invention relates to safety keys for locks with tumblers, and the principal object of the invention is to provide a key which cannot be used by any unauthorized person.

5 A safety lock as e. g. a Chubb or a Yale lock can usually be opened by anyone in possession of the proper key. It has therefore been proposed by several inventors to introduce keys with adjustable elements, which must be placed in certain relation to each other before the key can be inserted in the lock or can move the lock-bolts, in order to ensure security from an unauthorized opening of such locks. Adequate security has however not been attained with the known devices 15 of this kind.

In the case of the present invention the key is fitted with adjustable elements having means for their mutual interlocking, and the key can only open the lock to which it belongs, when its 20 elements have been placed beforehand in correct relation to each other and when the key is inserted in the correct position in the lock. The arrangement of the interlocking means, however, is such that the adjustable elements will be freely 25 movable and may occupy any position in relation to each other and to the main piece of the key as soon as this is withdrawn from the lock and as soon as the grip of the fingers on the handle of the key and their pressure on a 30 wing or other suitable element is released.

By this means only the person to whom the rule for the adjustment of the key-elements is known would be able to make use of the key for the opening of the lock in question. A forged, lost or copied key would therefore in itself not constitute the customary danger, as it could not be used by any unauthorized person, even if he knew to which lock it belongs.

By means of a sufficient number of adjustable key elements and a suitable number of possible adjustments of each of these elements, the possibility that a person who is not familiar with the adjustment rule might accidentally hit upon the correct adjustment, is reduced to such a minimum that the desired security is really obtained.

By a re-adjustment of the tumblers of the lock, the rule of adjustment for the elements of the safety-key may be changed at any time according to desire, so that if it is suspected that 50 the adjustment rule hitherto employed has come to the knowledge of an unauthorized person, the security will be reestablished.

In order to make the rule of adjustment easier to remember, each element may be fitted on its 55 surface with a cipher or letter corresponding to

every possible position of such an element to its adjacent elements, from which ciphers or letters those in a certain column should form a definite number or word when the elements are adjusted in their right positions.

This safety-key may be so arranged that when it is inserted in the lock and as long as the grip of the fingers on the key is retained, the interlocking of its elements in their correct positions is secured, but not however after the grip has been released, even if the key remains in the lock.

It may further be so arranged that the interlocking of the elements cannot be re-established before the key is withdrawn from the lock. Thus no unauthorized person finding a key in the lock can discover the rule of adjustment simply by taking out the key, because the key elements, during and after the withdrawal of the key, do not remain interlocked and therefore easily become displaced, as is always the case when the key is not actually in use. The elements can moreover be constructed in such manner that their displacement in relation to each other and to the main piece of the key is furthered by the movement of the key being withdrawn from the lock, or even so that they are forcibly displaced as soon as the key leaves the lock.

Further, the invention resides in the features of construction and the arrangement and combinations of parts hereinafter described and claimed, reference being had to the accompanying drawings, showing one form of the improved key to be used with a lock the tumblers of which adjust themselves on the insertion of the key, and wherein:

Fig. 1 is a longitudinal section of the key as inserted in a lock.

Fig. 2 is a transverse section on line A—B of Fig. 1.

Fig. 3 is a similar section on line I—K of Fig. 1.

Fig. 4 is a top end view of a stopping ring.

Fig. 5 is a section on line C—D in Fig. 1.

Fig. 6 is an end view of an adjustable element of the key.

Fig. 7 is a development of the cylindrical surface of the element in Fig. 6.

Fig. 8 is a front view of this element.

Fig. 9 is a section on line E—F—G—H of Fig. 1.

Fig. 10 is a top end view of a spring in the bottom of the key hole.

Fig. 11 is a top end view of another spring in the bottom of the key hole, and

Fig. 12 is a view into the key hole when the key is withdrawn.

Fig. 13 is an axial section of another embodiment of the invention showing a key inserted 5 in a lock.

Referring in detail to the drawings the safety key comprises a main piece 1 provided with a handle consisting of two branches 1a and 1b to which a yoke piece 2 is attached, having a 10 hole for fixing the key to a key-ring or the like. A cylindrical core 3 is movably located in a central bore 1c in the main piece 1 and carries on the extremity which protrudes between the two branches of the handle a wing 4 which can be 15 brought to rest against either of the two said branches.

A knob 5 on the core 3 can slide along a ringshaped surface of a recess 1d in the outer end of the main piece 1 and from this can slide 20 down a steep helical groove 1e in the inner cylindrical surface of the above mentioned central bore 1c in the main piece.

A helical spring 6 wound round the core 3 has its one end attached to the knob 5 and its other 25 to a knob 7 fixed in the main piece 1 and tends at the same time to turn the core 3 and to pull it downwards in such a way that the knob 5 will slide along the above mentioned ring-shaped surface and further into the helical groove, 30 thereby bringing the core as far through the main piece as is allowed by the wing 4 coming to rest against the one branch of the handle; this position is shown in full lines, Figs. 1 and 2 of the drawings, and is termed the "position of 35 rest."

An axial pressure against a head 8 on the free extremity of the core 3, followed by a pressure of the fingers against one side of the wing 4, will bring the core with its wing into the position shown by dotted lines on Fig. 1, which position corresponds to the state of the key before 40 its insertion in the lock and is termed the "interlocking position." The core will remain in this position as long as the pressure of the 45 fingers rests on the wing 4 and thereby counterbalances the influence of the helical spring 6. If the pressure is released the spring will bring the core back into its position of rest.

A stopper 9, shown separately in Fig. 4, is fixed 50 over the ring-shaped surface in the recess 1d of the main piece 1 and rests against a part of this surface; the core 3 passes through a hole 9a in this stopper, which prevents the knob 5 on the core from moving further out of the main 55 piece than corresponds to the resting of the knob against the ring-shaped surface.

On the inner side of this stopper 9 a crevice 9b allows the knob 5 to slide a certain distance along the ring-shaped surface after having left 60 the helical groove 1e, during the motion of the core 3 from its position of rest to its interlocking position. On the other hand, this crevice 9b ensures that the knob 5 slides from the ring-shaped surface down into the groove 1e, during 65 the motion of the core 3 from its interlocking position back into its position of rest, when the pressure on the wing 4 has been released.

The free extremity of the core 3 carries a 70 number of adjustable elements in the form of rings 10 which are free to slide and turn in relation to the core; the key shown on the plan has three rings 10, but the number of rings may be greater or smaller. The cylindrical surfaces of these rings 10 are each provided with tumbler 75 actuating means such as for instance one or

more cams 11 and/or grooves 12. The end surfaces of the rings 10 are provided with means for mutually interlocking the rings in a certain number of predetermined positions, such as cogs 10a as shown on Figs. 6-8; the end of the outermost ring 10 facing the head 8 being however smooth. The end surface of the main piece 1 facing the innermost ring 10 is furnished with cogs or other interlocking means corresponding to those of the rings. These means allow for a 10 certain number of adjustments of the rings in relation to each other and to the main piece, (in the form shown on the drawings there are eight different adjustments of each element) and at the same time lock the adjustment when 15 the rings are pressed against each other and against the main piece by means of the head 8 at the extremity of the core 3. With eight different adjustments of each ring in relation to the main piece and to the adjacent rings and 20 with three rings in all, there will be 512 different combinations possible, with four rings there will be 4096, and so on.

The part 1f of the main piece 1 facing the rings 10 is formed like a cylinder, having the 25 same diameter as the rings. This part 1f may be furnished with one or more belts of cams 11 and grooves 12 corresponding to those on the rings, in this case one belt 1g. Following this belt there is another belt provided with cogs 1h, behind which a collar 1k on the main piece limits the depth to which the key can be inserted in the lock.

The length of the core 3 is such that the head 35 8 will keep the rings 10 pressed against each other and against the extremity of the main piece, if the core is brought into its "interlocking position" mentioned above, i. e. with the wing 4 resting against one of the branches of the handle, the right one on the drawings. Thus, if 40 the rings 10 have been adjusted in their right positions in relation to each other and to the main piece, the core 3 will keep them interlocked in this position, as long as the core itself is kept 45 in its interlocking position.

When the key is not in use, the core will be 50 in its "position of rest" into which it automatically moves as soon as the grip of the fingers on the handle of the key releases the pressure on the wing 4. The rings 10 will then be free to move along and around the core 3 and they will shift 55 their position under the influence of spontaneous external forces. Every time the key is to be used, the elements will therefore have to be adjusted afresh.

The corresponding lock in the form shown on the drawings is furnished with a cylindrical centre piece 13 the turning of which by means of the inserted key will result in the displacement of the bolt as usual. This centre piece turns inside a cylinder 14 which is fixed to the main part of the lock 15 which again is mounted on the inner side of the door in such manner that the cylinder 14 fits into a hole in the door-frame and protrudes through the hole almost to the outer side 65 of the door-frame, where the hole is covered by an escutcheon 20. The centre piece 13 is secured by appropriate means against removal from outside, even if the escutcheon has been taken off.

The centre piece 13 is furnished with a cylindrical bore corresponding to the external diameter of the rings 10 which bore guides the key on its insertion in the lock. The cylindrical surface of the bore is furnished with a number of slots of rectangular cross-section, the number of slots to 70

correspond with the number of adjustments of the rings in relation to the main piece of the key, e. g. in the form shown on the drawings there are eight slots. The cross-section of the slots corresponds with the cross-section of the cams on the rings and on the main piece of the key, also with the cross-section of the cogs on the cylindrical part of the main piece. The diameter of the bore near the bottom corresponds to the bottom of the slots, thus providing the necessary play for the cutting of the slots. In the bottom of the bore there is a hole for a screw 24.

Corresponding to the cams and/or grooves of the main piece and rings of the key, the centre piece 13 of the lock is furnished with belts of radially movable tumblers 16, the number of tumblers in each to be the same as the number of slots in the centre piece, as shown in Fig. 9. The tumblers slide in holes in the centre piece 13 and may e. g. be furnished with heads to prevent them from being pressed further in than will leave a cylindrical passage between their extremities, with a radius corresponding to the distance from the axis of the core 3 of the key to the bottom of the grooves in the rings 10. Pistons 17 which slide in radial holes in the cylinder 14 press against these heads under the influence of helical springs 18. When the door is locked the position of the centre piece 13 in relation to the cylinder 14 will be such that each tumbler 16 will be opposite a piston 17. The springs 18 are kept in place by a tube 19 encasing the cylinder 14 and secured to this by a couple of screws. By an axial displacement of the tube 19 along the cylinder 14 the holes containing the helical springs, pistons and tumblers are uncovered, so that these elements can be replaced by others or exchanged.

The length of the tumblers 16 is adjusted in such manner that the points of contact between the tumblers and the pistons will correspond with the cylindrical surface of the centre piece 13 when the key, after having had its elements adjusted in the right way, is inserted in the lock in its right position. In this case the surface formed by the cylindrical part 1f of the main piece 1 of the key and of the rings 10 and also of the cams and grooves will press against the extremities of the tumblers, thereby moving them to the necessary distance outwards from their position of rest. As long as the key is not inserted in the lock a certain number of the pistons 17 will protrude with their extremities into the holes in the centre piece 13, and thereby prevent the turning of this piece and accordingly also prevent the opening of the lock; if the adjusted key is inserted to the right depth the above mentioned locking of the centre piece 13 ceases.

By the interchanging of some sets of pistons 17 and corresponding tumblers 16 with other sets, the adjustment of the key elements for the opening of the lock may be altered, e. g. if an unauthorized person has found out the rule of adjustment hitherto used.

The number of cams and grooves (in each belt of the key), as well as their mutual arrangement, being variable, an adequate number of variations is possible in order to avoid two locks with their keys becoming identical; the number of belts may also be varied.

When the grip of the fingers which keeps the wing 4 on the end of the core 3 pressed against the branch on the handle of the inserted key is released, the core will turn and slide down into its position of rest, thereby penetrating the bore

in the centre piece of the lock to a greater depth, on account of which this bore itself must have a corresponding depth. A cup-shaped spring 22 with fingers, one for each slot in the centre piece, prevents the rings 10 from sliding further into the bore, when the core 3 with its head 8 slides further downwards as above described. A second spring 21 with fingers 21a resting against a cylindrical part 8a of the head 8 when this head has protruded to its greatest depth in the bore, 10 will prevent the re-turning of the core 3 and consequent movement into its interlocking position, as the cylindrical surface 8a of the head is formed like a ratchet wheel.

Both springs 21 and 22 are fixed in the bottom 15 of the bore by means of a screw 24 with a washer 23; the fingers of the springs protrude into the ends of the slots, thus preventing the turning of the springs.

On the withdrawal of the key from the lock, 20 the friction between the extremities of the tumblers 16 and the surface of the rings 10 prevents these rings from sliding outwards with the key until the head 8 reaches the rings 10 and starts to press them out; this means that the rings 10 25 are removed from the end of the main piece of the key. If the slots in the centre piece of the lock are made to follow helical lines of great pitch and if the cams and grooves of the rings, etc. are formed accordingly and also the position 30 of adjustment of the elements to each other corresponds to the helical slots, the rings will turn around the core and shift their positions in relation to the main piece of the key on its withdrawal from the lock, the release of the grip of 35 the fingers having previously allowed the core with its head 8 to turn and slide into its position of rest. On the insertion of the adjusted key in the lock with helical slots, the entire key will of course have to be turned to a depth corresponding to the depth to which the foremost ring penetrates the bore.

In order to obtain a further security against an unauthorized use of the key the lock may according to the invention be so constructed that 45 even if the key has been left correctly adjusted in the lock this cannot be opened as soon as the grip of the fingers on the wing 4 is released. This is obtained by an additional set of tumblers 25 for cooperation with the head 8 of the core 3. 50 The tumblers 25 are placed in the centre piece 13 in alignment with the head 8 when this latter is in its lower or released position. The tumblers 25 are pressed inward by springs 27 through the medium of pistons 26 sliding in radial holes in 55 the cylinder 14. The outer ends of the holes are closed by a cylindrical cover 28 keeping the springs 27 in place. The lengths of the tumblers 25 and the heads are so adjusted that, when the core 3 is in its upper position, the tumblers protrude into the key hole and the top of the heads are in alignment with the outer surface of the centre piece 13 thus allowing this centre piece to be turned by means of a correctly adjusted and interlocked key. As soon, however, as the wing 4 60 is released the core 3 will move downward, and its head 8 will force the tumblers 25 outward against the action of the springs 27. The heads of the tumblers consequently will reach into the cylinder 14, as shown in Fig. 1, and it is impossible to 65 turn the centre piece 13 in relation to the cylinder 14 even if all the rings 10 are correctly adjusted. An unauthorized person finding a correctly adjusted key inserted in the lock will consequently be unable to use the key and to open the lock. 75

Before the lock can be opened it is necessary that the key is withdrawn from the lock, adjusted anew and again inserted in the lock, and the opening must be effected before the wing 4 is released.

5 Fig. 12 shows the key-hole before the insertion of the key. As a great number of tumblers will have to be moved in an attempt to pick the lock by means of jimmies, the narrow space in which 10 the jimmies have to work will practically prevent the success of such attempts.

Fig. 13 shows another embodiment of the invention, the springs 21 and 22 are replaced by other means for preventing the rotation of the 15 core 3 in its released position and the sliding down of the rings 10, when the core 3 is released. In this embodiment the core 3 is hollow being provided with an axial bore extending through 20 the head 8. In the bottom of the key-hole in the lock is fixed a stem 30 which extends axially in the key-hole and which passes into the bore in the core when the key is inserted in the lock. The stem 30 is provided with longitudinal grooves 25 31 in its cylindrical surface and in an extension 32 of the bore within the head 8 there is located a spring 33 which has a number of lugs or the like for cooperation with the grooves 31. Instead of a single spring 33 with lugs a number of shorter springs may be used the ends of which cooperate 30 with the grooves 31. For preventing the rings 10 from moving too far into the key-hole a ring 34 is located in the inner wall of the center piece 13. The head 8, which in this embodiment has 35 no outer ratchet teeth but has an even outer surface, may when the key is inserted in the key-hole pass through the ring 34, but the rings 10 will be stopped by this ring 34, or their diameters are too large for allowing them to pass. The hollow core in passing over the stem 30 and 40 the lugs or ends of the springs 33 are hereby sliding in the grooves 31. The springs are so fixed in the head that they can slip from one groove 31 to another when the core is turned in one direction but prevent rotation in the other 45 direction like ratchet pawls.

In this embodiment further the cover for the piston holes in the cylinder 14 consist of a number of rings 29 one for each belt of pistons each ring 29 is provided with a hole which by turning 50 the ring about the cylinder 14 may successively uncover the holes of the corresponding belt of pistons.

With locks of for example the Chubb system, the principle of the present invention could be 55 introduced by providing the tumblers of such locks with openings corresponding to the adjustment of the cams on the rings to each other. If one of the cams is not adjusted in the right position in relation to the main piece of the key, the 60 corresponding tumbler will either be raised too much or too little, in neither case can the lock be opened.

Having thus described our invention we claim:

1. A safety key comprising a main piece, a 65 handle fixed thereto, a core axially penetrating the said main piece and having a free portion protruding opposite the handle, and a number of ringshaped adjustable elements arranged slidably on and turntable around the said free portion of the core, the adjustable elements being provided with tumbler actuating means on their outer surfaces and with means for interlocking the elements in a certain number of pre-arranged 70 positions on their end surfaces facing each other.

2. A safety key comprising a main piece, a

handle fixed thereto, a core axially penetrating the said main piece and having a free portion protruding opposite the handle, and a number of ringshaped adjustable elements arranged slidably on and turntable around the said free portion of the core, the adjustable elements being provided with tumbler actuating means on their outer surfaces and with cogs on their end surfaces facing each other.

3. A safety key comprising a main piece, a handle fixed thereto, a core axially penetrating the said main piece and having a free portion protruding opposite the handle, a number of ringshaped adjustable elements arranged slidably on and turntable around the said free portion of the core, the adjustable elements being provided with tumbler actuating means on their outer surfaces and with means for interlocking the elements in a certain number of pre-arranged 15 positions on their end surfaces facing each other, 20 and means for fixing the interlocking of the elements.

4. A safety key comprising a main piece, a handle fixed thereto, a cylindrical core axially displaceable in a bore in said main piece and protruding from the bore to both sides, a number of adjustable elements with tumbler actuating means and interlocking means arranged around the said core on the end opposite the handle, and a head on said end of the core for pressing the 30 said elements against each other and against the main piece.

5. A safety key consisting of a main piece, a handle fixed to one end of said main piece, an axial bore in said main piece, a helical groove 35 in the inner surface of said bore, a cylindrical core freely movable in said bore, a wing on the end of said core protruding into the handle, a number of adjustable ringshaped elements having tumbler actuating means and interlocking 40 means on the end of the core protruding opposite the handle, a head on the end of said core opposite the handle, a knob on the core located in the said helical groove and a spring attached to the core and the main piece.

6. A safety key consisting of a main piece, a handle fixed to one end of said main piece, an axial bore in said main piece, a helical groove in the inner surface of said bore, a cylindrical core freely movable in said bore, a wing on the end 50 of said core protruding into the handle, a number of adjustable ringshaped elements having tumbler actuating means and interlocking means on the end of the core protruding opposite the handle, a head on the end of said core opposite the handle, a cylindrical surface of said head provided with ratchet teeth for cooperation with fingers on a spring in the bottom of the key hole in a lock, a knob on the core located in the said 55 helical groove and a spring interposed between the core and the said main piece.

7. A safety key consisting of a main piece, a handle fixed to one end of said main piece, an axial bore in said main piece, a helical groove in the inner surface of said bore, a cylindrical core freely movable in said bore, a wing on the end of said core protruding into the handle, a number of adjustable ringshaped elements having tumbler actuating means and interlocking 65 means arranged side by side on the end of the core protruding opposite the handle, a head on the end of said core opposite the handle, a cylindrical surface of said head provided with ratchet teeth for cooperation with fingers on a spring in the bottom of the key hole in a lock, 70

5 a knob on the core located in the said helical groove, a spring fixed with one end to the core and with the other end to the main piece, a cylindrical belt on the main piece adjacent the adjustable elements said belt having tumbler actuating means on the cylindrical surface and interlocking means on the end surface, a belt of cogs on the main piece for cooperation with cogs on the center piece of a lock and a collar on the main piece for limiting the depth to which the key can be inserted in a lock.

10 8. A safety key consisting of a main piece, a handle fixed to one end of said main piece, an axial bore in said main piece, a helical groove in the inner surface of said bore, a cylindrical core freely movable in said bore, a wing on the 15 end of said core protruding into the handle, a number of adjustable ringshaped elements having tumbler actuating means on their cylindrical surfaces and interlocking means on their end surfaces arranged on the end of the core protruding opposite the handle, a head on the end of said core opposite the handle, a cylindrical surface of said head provided with ratchet teeth for cooperation with fingers on a cupshaped spring in the bottom of the key hole in a lock, 20 a knob on the core located in the said helical groove, a spring urging the core in a direction opposite the handle, a cylindrical belt on the

main piece adjacent the adjustable elements said belt having tumbler actuating means on the cylindrical surface and interlocking means on the end surface, a belt of cogs on the main piece for cooperation with cogs on the center piece of a lock and a collar on the main piece for limiting the depth to which the key can be inserted in a lock. 5

9. A safety key consisting of a main piece, a handle fixed to one end of said main piece, an axial bore in said main piece, a helical groove in the inner surface of said bore, a cylindrical hollow core freely movable in said bore, a wing on the end of said core protruding into the handle, a number of adjustable ringshaped elements having tumbler actuating means and interlocking means slidably arranged on the core, a head on the end of said core opposite the handle, springs in the cavity of said head acting as resilient ratchet teeth for cooperation with a 20 grooved stem in the bottom of the key hole in a lock, a knob on the core located in the said helical groove and a spring interposed between the core and the main piece.
